LIQUID-GAS CONTACT TOWER

Edward P. Fleming, Los Angeles, Theodore C. Fitt, Selby, and Robert B. Muse, Orinda, Calif., assignors to American Smelting and Refining Company, New York, N. Y., a corporation of New Jersey

Application December 31, 1953, Serial No. 401,588

2 Claims. (Cl. 261—114)

This invention relates to a sectionalized liquid-gas contact tower. More particularly, it relates to a sectionalized tower comprised of lead.

In accordance with past practice, liquid-gas contact towers have been used in which the walls were of rigid unitary construction which bore the weight of the tower. Where bubble cap trays were used, such trays were attached to the tower walls and had no function in so far as wall load-bearing purposes were concerned.

In practice, the prior construction has been found to be relatively expensive and to involve rather complicated erection procedure. Moreover, it is necessary that a part or all of the tower proper be constructed of high strength metal in order that the load-bearing parts possess the required mechanical strength. However, the use of such metal in the tower proper has been found to be undesirable when the tower is operating under corrosive conditions.

For example, even when the tower proper was fabricated of a special corrosion-resistant chrome-steel alloy, applicants have found the tower life to be undesirably low and maintenance costs to be relatively high when such a tower was used for the absorption of sulfur dioxide from a gaseous mixture or the desorption with steam of an absorbent laden with sulfur dioxide, and chlorine or chlorides were present in the system.

Applicants have attempted to take advantage of the excellent corrosive resistant qualities of lead and lead alloys by using such metal in the prior construction. It was found that towers, especially towers of the tray and bubble cap type, of a practicable size could not be constructed and erected in accordance with the prior practice when the tower proper was composed of lead or lead alloys or similar low-strength metal because of the excessive softness and lack of mechanical strength in such metals.

It was found further that towers constructed in accordance with the prior art and fabricated of lead-clad steel, in which the lead was bonded to the steel, were also unsatisfactory in that the lead became separated from the steel, especially under the variable temperature conditions existing within the tower during its operation. Under these conditions, the corrosive fluids leaked into the resulting interstitial space between the metals, corroded the susceptible ferrous metal and resulted in expensive maintenance repairs and shortened operating periods as well as reduced life of the tower.

The principal advantage, as well as the principal object, of the invention is that it overcomes the above-mentioned difficulties of the prior construction. Another advantage and object is that it permits the construction of liquid-gas contact towers of a practicable size, and particularly towers of the tray and bubble cap type, in which the tower proper is fabricated of lead or lead alloys or of similar soft, low-strength metal. A further advantage and object of the invention is that it provides a relatively simple and cheap method of constructing liquid-gas contact towers. These and other objects and ad-

2

vantages will become apparent from the following, more detailed description of the invention.

For the purpose of illustrating the invention, there are shown in the accompanying drawings, forms thereof which are at present preferred. It should be understood, however, that the drawings are given for purposes of illustration and that the invention in its broader aspects is not limited thereto.

In the drawings, Fig. 1 is an elevational view, partly in section, of a liquid-gas contact tower embodying the invention and which is provided with tray and bubble cap assemblies.

Fig. 2 is a cross-sectional view of the tower of Fig. 1 taken along line 2—2 of Fig. 1 in the direction of the arrows.

Fig. 3 is a view illustrating a tower section used in assembling a tower.

Fig. 4 is an enlarged fragmentary view showing the details of the structure of Fig. 1.

Fig. 5 is a fragmentary section on line 5—5 of Fig. 4 taken in the direction of the arrows.

Fig. 6 is a view illustrating a modified sealing means for the various sections of the tower.

Fig. 7 is a view illustrating another modified sealing means for the various sections of the tower.

Fig. 8 is a sectional elevation view of a modified tower.

Fig. 9 is a cross-sectional view on the line 9—9 of Fig. 8 taken in the direction of the arrows.

Referring now to Fig. 1 of the drawings, there is shown a sectionalized liquid-gas contact tower designated generally by the numeral 10, and an open outer framework comprised of the vertical structural members 11 which may be suitably laterally supported by the members 12. Disposed within the framework at vertically spaced, and preferably at uniformly vertically spaced, intervals are a plurality of tower wall sections 14—20. Each of the wall sections is of unitary construction. Each extends around and conforms to the desired lateral perimeter of the tower and forms by itself the vertical walls of the tower for each section's portion of the tower. Each of the wall sections is individually supported within the framework by inwardly projecting supporting means 22—29 which are attached to the framework at vertically spaced intervals corresponding generally to the position of the wall sections 14—20. For each of the resulting lateral openings which are perimetric of the tower between adjacent vertically spaced wall sections, there is provided separate means for sealing the openings against fluids.

A plurality of curtain sections 31—37 are provided, one for each of the perimetric space portions between immediately adjacent wall sections. Each curtain section extends around the perimetric opening and is supported by one of the two wall sections immediately adjacent each curtain section in fluid tight relationship to the supporting wall section. Each such curtain section also extends adjacent to the other of the adjacent wall sections and is vertically yieldably sealed therewith against fluids. Each curtain section thereby forms a tower wall extension for the individually supported wall section which supports the particular curtain section.

Referring now to Figs. 1, 2, 4 and 5, there is shown a circular tray and bubble cap type of tower embodying the invention. The tower proper is fabricated of a soft corrosion-resistant metal such as lead or lead-base alloys. The open framework formed by the members 11 and 12 is fabricated of a high strength metal such as, for example, a ferrous metal such as steel; and inwardly projecting supports 22—29 are annular angle rings also fabricated of the same or similar high strength metal. The angle rings may be attached to the vertical members 11.

by any suitable means such as by the nuts 41 and the bolts 40, as illustrated in Fig. 4.

The wall sections 14-20 are thick in their lateral dimensions, thereby affording a high load-bearing capacity for these soft metal members. The thickness of these latter members may vary, depending upon the lateral dimension of the tower and the vertical length of the wall sections. In general, the wall sections are about 1-4 inches thick and the vertical length of each section may be about 4-12 inches and generally about 6 inches in their vertical extension. The bottom of each of the wall sections 14-20 rests upon the top surface of the annular supports 22-29 respectively so that each of the wall sections is individually supported in its desired position in the framework.

Each of the intermediate wall sections 15-19, between the top wall section 14 and the bottom wall section 20, have integrally formed therewith a horizontal tray portion 42. Each of these tray portions is provided with a plurality of openings 43 adapted to receive gas or vapor riser pipes. The top wall section 14 and the bottom wall section 20 are provided with tray portions 44 and 45 respectively which are without riser pipe openings and form top and bottom closures respectively for the tower. The horizontal portions 42, 44 and 45 are preferably relatively thin as compared to the thickness of their respective wall sections. Generally, these horizontal portions are about $\frac{1}{2}$ -2 inches thick. With this construction, each of the wall sections 14-20 constitutes a horizontal tray having a thick downwardly depending tower-wall-forming flange.

Vapor riser pipes 46 of conventional design may be supported in the openings 43 of the intermediate trays in any suitable manner, for example by attaching therein with welding. The bubble caps 47, also of conventional design, may be supported over the riser pipes in any suitable manner, for example by welding to the horizontal tray portions 42. Each of the intermediate trays is also provided with a down pipe 48.

In operation, vapor or gases contact liquids in the tower in a conventional manner. Thus, a liquid which may be introduced through the top of the tower through inlet 49, passes downwardly through the tower from tray to tray through the down pipes 48 and then leaves the tower through the outlet 50. A quantity of fluid is retained on each tray to a depth regulated by the position of the top of each of the down pipes 48. Gas or vapor may be introduced through inlet 51, passing upwardly through the tower and leaving the tower through outlet 52. In its upward passage, the gas passes from tray to tray, rising upwardly through the riser pipes 46. It then reverses its direction, passing downwardly through the annulus between the riser pipes and the bubble caps. It again reverses its direction, passing around the bottom of the bubble cap, and then passes upwardly through the liquid retained on each of the trays, thus making a series of intimate contacts with the liquid as the gas passes through the tower.

Each of the wall sections 14-20 may be provided with a support grid 53 attached to the inside surface of the wall and to the bottom of the horizontal tray portion of each wall section. Preferably, each grid is integrally formed with the side wall and tray portion to which it lends support. Preferably also, the grids extend radially from the center of the tray portion of each tray, as shown in Fig. 2. The supporting grids are an important feature in towers fabricated of a soft material, especially in tray and bubble cap-type towers, as towers of larger diameter than would otherwise be possible can be constructed by their use.

The curtain sections have substantially no load-bearing function other than to be able to carry their own weight. They, therefore, may be thin as compared to the wall sections 14-20, for example, about $\frac{1}{16}$ - $\frac{1}{2}$ inch in thickness. In the preferred construction illustrated in Figs.

1-4, the curtain sections 31-37 depend downwardly from and are attached to and supported by the top wall section 14 and intermediate wall sections 15-19 respectively—there being no depending curtain from the lowermost wall section 20.

As is shown in Figs. 1 and 4, each of the wall sections 14-19 may be provided with an annular recess 54 extending around its lower inside edge. The dimensions of each such recess may be such as to receive the upper portion of a curtain wall with the inside surface of the curtain wall flush with the inside surface of the wall section above the recess in the manner shown particularly in Fig. 4. Each of the curtains may be attached and sealed to its respective wall section by means of the welding strips 55 and 56 by so-called burning. Each of the curtains also extends downwardly with its lower edge terminating close to but out of contact with the top of the wall section immediately below it; thereby permitting vertical motion of the curtain with expansion and contraction of the tower.

Each of the openings 57 perimetric of the tower between the bottom of each curtain and the top of the adjacent wall section which is immediately below the curtain, is sealed against fluids by a thin annular strip 58 of arcuate form in vertical section. The top edge of each sealing strip may be sealed and attached adjacent the bottom of the curtain with which it is associated, by the welding 59. The lower edge of the sealing strip may be sealed and attached to the tray immediately below the curtain by the welding 60. For greatest convenience in assembling the sectional tower, the sealing strips are disposed outwardly of their respective curtains, with the bottom edge of the strip attached to the top of the wall section below the curtain and adjacent to the outside perimeter of the latter wall, as illustrated most clearly in Figs. 4 and 5. The thin strips, due to their arcuate form, are vertically yieldable and provide a yieldable seal which, upon expansion and contraction of the tower, is not broken.

In the space enclosed by each of the sealing strips there may be disposed an annular curtain support ring 61. Each such ring may be attached to the top of the wall section which is immediately below each curtain, by the welding 62. Each of the curtain support rings 61 are disposed, as shown, outwardly of and adjacent to the curtain which the ring supports. Each support ring extends vertically above the lower edge of the curtain with which it is associated and thereby limits the outward motion of the curtain. In general, the use of the support ring together with the arcuate sealing ring is preferred, especially in larger towers, i. e., those having a diameter of 4 feet or more, or in towers operating under a pressure which is slightly above atmospheric pressure. With this preferred construction, the ring 61 may be provided with drain holes 63 which permit liquid which may collect in the spaces 64 to drain back onto the trays.

Instead of using the arcuate sealing strip 58 illustrated in Figs. 1, 2, 4 and 5, the modified forms shown in Figs. 6 and 7 may be used, especially in small towers, to provide a vertically yieldable seal against fluids between each curtain and either or both of the wall sections immediately above and below each curtain. In the modification of Fig. 6, the overlapping portions of the downwardly depending curtains, represented in this figure by the curtain 32, and the support ring 61 slidably engage each other so that the support ring functions both as a seal and support for the curtain.

In the modification of Fig. 7, the ring 61 is attached to the lower tray and to the curtain 32 above the tray, by the weldings 65 and 66 respectively. The curtain extends upwardly and terminates close to but out of contact with the upper edge 67 of the recessed portion 54 of the upper tray. The outside surface of the upper portion of the curtain slidably engages and is supported by the overlapped portion of the vertical inside surface 68 of

the recess. In this modification, each curtain represented by numeral 32, instead of being attached to, may merely rest upon, the top of the tray (represented by numeral 16), below it.

The present construction may also be used for towers other than the tray and bubble cap type, including packed towers or spray towers. Figs. 8 and 9 illustrate such a modification in which the tower is a spray tower. As shown in these figures, the tower is similar to that of Fig. 1 except that the intermediate wall sections, represented by the numerals 70 and 71 in Fig. 8, between the top wall-closure section 14 and the bottom wall-closure section 20 are not provided with the horizontal tray portion 42, the riser pipe 46, the bubble caps 47 or the down pipes 48. These intermediate wall sections may be, and preferably are, provided with support grids 53, especially where the tower is fabricated of a soft metal.

Liquid is introduced at the top of the tower of Fig. 8 through the sprinkler pipes 72 and falls as a free-falling spray to the bottom section 20 from which it is withdrawn from the tower through outlet 50. Gases which are to contact the liquid enter the tower through inlet 51, passing upwardly through the tower and the liquid spray therein and leave through gas outlet 52. In the modified tower, the individual wall sections preferably are also provided with the arcuate sealing strip 58. As illustrated in Fig. 8, curtain support rings need not be used (and this is also true for the tower of Fig. 1) although such rings may be provided if desired. The modification of Figs. 6 and 7 may also be used in the tower of Fig. 8 to seal the perimetric openings between each of the curtain sections and the wall sections immediately above and below each curtain.

As indicated earlier, the invention is most useful for towers composed of metal of low mechanical strength, such as lead or lead base alloys. It is particularly useful for towers of the tray and bubble cap type. For best results, an antimonial lead alloy containing about 6-12% and preferably about 10% of antimony is used for the individually supported wall sections and the grids therefor. Antimonial lead alloys containing antimony in this range are preferred as it has been found that an antimony content below about 6% results in an alloy that is unduly soft, while antimony contents above 12% results in an alloy which is unduly brittle. Antimonial lead alloys containing 6-12% antimony are also preferred for the trays, flanges and grids in a tray and bubble cap type of tower. The rest of the tower, including any one or more of the welding connections, curtain walls, sealing means, support rings for the curtain walls and, where used, bubble caps, riser pipes, or down pipes may also be fabricated of these alloys or other lead alloys including ordinary lead. The open outer framework and the inwardly projecting supports attached thereto may be fabricated of any high strength metal which preferably is a ferrous metal such as steel.

Preparatory to assembling a tower embodying the invention, each of the wall sections 14-20 preferably is individually cast. Where used, the recess 54, the grid 53 and the horizontal tray portion with the vapor riser holes as required, are cast with the wall sections as an integral part of each wall section. The wall section intended to be the lowermost wall and closure section may then have attached to its top a curtain support ring, if such a ring is to be used. As no curtain is suspended from the bottom of this lowermost wall and closure section, no curtain receiving recess need be provided in it. The intermediate wall sections may be individually assembled as illustrated in Fig. 3. As illustrated in this figure, each wall section, represented by the numeral 16, has its curtain section, represented by the numeral 33, suitably attached in the recess 54 by the weldings 55 and 56. A curtain supporting ring 61, where used, is welded to the top of each wall section with the welding 62. The

down pipe 48, vapor riser pipes 46 and the bubble caps 47, also where used are likewise suitably attached by welding. The upper wall and closure section 14 may also be pre-assembled with its curtain 31 suitably attached by welding. No curtain sealing ring need be attached to the top of section 14 regardless of whether or not such rings are used with the other wall sections 15-20.

In assembling the tower, the open outer framework represented by the numerals 11 and 12, is first erected. The 10 wall support 29 may then be attached to the framework, after which the lowermost wall section 20 may then be lowered through the top of the framework until the bottom of this wall section rests upon the support 29. If desired, the support 29 may be attached to the framework after 15 the wall section 20 has been lowered to its intended position in the framework. Thereafter, if arcuate sealing strips 58 are to be used, the lowermost sealing strip 73 (see Fig. 1), fabricated either as a one-piece ring or a split ring, is lowered through the top of the framework and is allowed to rest loosely on the top of wall section 20. The next support 28 is then lowered through the top of the framework to its desired position therein. The support 28 may then be attached to the framework. The next intermediate wall section 19, assembled as illustrated 20 in Fig. 3, is then lowered through the top of the framework to its position resting upon the support 28. During 25 the last stage of its lowering, the lower edge of the curtain 37 which is attached to the wall section 19, is carefully inserted through the upper edge of the sealing strip 73. The above steps for attaching the other wall supports, 30 sealing rings and intermediate wall section units may be repeated for each of the wall supports 27-22 and the wall section units 18-14 until all of the wall sections are positioned in the framework. The lower and upper edges 35 of each of the sealing strips may be welded respectively to the top of the wall section and adjacent the bottom of the curtain with which the particular strip is associated, after each section is inserted in the framework or after all of the sections have been inserted. The fluid inlet and 40 outlets may be connected to the tower and the tower is then ready for operation.

It should then be noted that each of the arcuate sealing strips, when they are used, may be multi-sectional in form 45 rather than in the one piece or split ring form. In the multi-sectional form, the sealing rings may be attached 45 in position at any time after the wall section with which a particular ring is associated has been positioned in the tower. This may be accomplished by inserting the individual section of each strip through the open sides of the 50 framework. The wall supports 22-29 may likewise be multi-sectional and may or may not extend around the entire perimeter of the tower. Such section supports may also be inserted through the sides of the framework and attached thereto after each wall section has been lowered 55 to its intended position in the framework. In such event, each of the arcuate sealing strips may be welded either to the curtain or the top of the wall section with which the particular curtain is to be associated before the wall section is lowered into the framework. The unattached 60 edge of the sealing strip may then be attached at any time after its particular wall section is in position in the tower.

The present invention may be embodied in other specific forms without departing from the spirit or essential attributes thereof. Thus, for example, instead of being 65 circular in cross-section, the towers may have a rectangular or other polygonal cross-sectional shape. It is, therefore, desired that the present embodiments be considered in all respects as illustrative and not restrictive, reference being had to the appended claims rather than to the foregoing description to indicate the scope of the invention.

What is claimed is:

1. In a tower for treating corrosive fluids, an open outer tower supporting framework, a plurality of vertically spaced thick wall sections disposed within said framework, each of said wall sections forming the lateral perimeter

7 of the tower and the vertical walls of the tower for the particular section's portion of the tower, inwardly projecting and vertically unyieldable support means attached to said framework for each wall section, the base of each wall section resting upon its respective unyieldable support means, whereby the wall sections are supported within said framework in fixed spaced vertical relationship to the framework and to each other with the top of each wall section spaced from the bottom of the wall section immediately above it, the uppermost and lowermost sections including end walls forming top and bottom closures for said tower, said wall sections being fabricated of antimonial lead containing about 6-12% antimony, separate sealing means fabricated of lead for each of the perimeter openings between adjacent wall sections forming a 15 yieldable seal against fluids for said openings, liquid inlet and outlet means for said tower, and gas inlet and outlet means for said tower, whereby the gas and liquid may be brought into intimate contact in said tower, each of the wall sections thereby being free to expand and contract independently, and each wall section being free of the weight of adjacent wall sections and the weight of the rest of the tower, regardless of expansion and contraction of any part of the tower.

2. A tower according to claim 1, each of said wall sections having a supporting grid which is encompassed by the wall section, each said grid also being fabricated of said antimonial lead, said separate sealing means comprising a thin lead curtain section depending downwardly from and extending around the inside perimeter of the uppermost and intermediate wall sections, each of said curtains also extending downwardly and terminating close to but out of contact with the top of the wall section immediately therebelow, each of the said intermediate wall sections and the lowermost wall section having on the top 25

5 thereof a curtain support member fabricated of lead and which extends around the top of the wall section adjacent the latter's perimeter and which also extends upwardly above the lower edge of the curtain depending from the wall section immediately thereabove, each of such curtain support members being positioned between the outside perimeter of the wall section to which it is attached and the outside surface of the curtain with which it is associated, thereby limiting the outward motion of the curtain wall when the latter is subjected to pressure on its inner surface, and a yieldable lead sealing strip of arcuate form in vertical section for each of said curtains, each such sealing strip extending around the curtain's perimeter and being disposed outwardly of the curtain and the associated curtain support, each such sealing strip being attached at its upper edge to the curtain perimeter adjacent the curtain's bottom edge but above the top of the curtain's support, the lower edge of each such sealing strip being attached adjacent the outside perimeter of the wall section which is immediately below the curtain section. 10 15 20
